UNITED STATES PATENT OFFICE.

LOUIS K. SCOTFORD, OF CHICAGO, ILLINOIS.

HAND-PRINTING GUIDE.

SPECIFICATION forming part of Letters Patent No. 548,226, dated October 22, 1895.

Application filed May 10, 1894. Serial No. 510,766. (No model.)

To all whom it may concern:

Be it known that I, LOUIS K. SCOTFORD, of Chicago, in the county of Cook and State of Illinois, have invented certain new and useful 5 Improvements in Hand-Printing Guides; and I do hereby declare that the following is a full, clear, and exact description thereof, reference being had to the accompanying drawings, and to the letters of reference marked thereon, 10 which form a part of this specification.

This invention relates to improvements in type-guides for securing the proper spacing and alignment of the letters and words when printing by hand by means of individual type.

15 The object of the invention is to provide an improved construction in devices of the character referred to; and it consists in the matters hereinafter set forth, and particularly pointed out in the appended claims.

20 In the accompanying drawings, Figure 1 is a top plan view of a type-guiding device embodying my invention in one form. Fig. 2 is a transverse section thereof, taken on line 2 2 of Fig. 1. Fig. 3 is a similar view showing 25 the slide in the position indicated by dotted lines in Fig. 1. Fig. 4 is a bottom plan view of the slide alone. Fig. 5 is a detail of a construction of groove and engaging-flange somewhat modified from that previously shown.

30 In said drawings, A designates a guiding-strip adapted to be placed upon the surface to be printed, and B a metallic slide mounted upon said strip A and capable of longitudinal motion relatively thereto. As herein shown, 35 the guide-strip A is made in the form of an ordinary straight ruler provided in its upper surface or top a with one or more longitudinal grooves or saw-kerfs, in this instance two in number and designated by a' and a^2 . The

40 slide B, as herein shown, comprises a flat body portion or web b , provided along its rear edge with a depending flange b' , adapted to enter and slide within either of the grooves a' a^2 , and along its front edge with a second depending flange b^2 , to which a forwardly-projecting arm b^3 is rigidly attached. The

45 width of the intermediate web b is made greater than the distance between the rear-most groove a' and the front edge a^3 of the

50 guide-strip, so that when the rear flange b' is inserted in either of the grooves the front flange b^2 will depend in front of said front edge a^3 of the guide-strip and the under surface of the web will rest upon the top a of

said strip. A projecting knob or handle b^4 is 55 herein shown on the top of the slide to facilitate the handling of the same.

C designates one of a font of individual type, in this instance made with a wooden body c and a rubber printing or type surface c' , the wooden body being shaped at its upper end to form a handle portion c^2 , adapted to be grasped between the fingers. The body c of the type is made rectangular in cross-section, and is thereby adapted to fit within 65 the corner formed at the juncture of the front flange b^2 of the slide B with the forwardly-projecting arm b^3 thereof. Obviously, therefore, by so thrusting each type as it is used into the corner of the front flange and 70 arm and moving the slide along the proper distance after making the impression of each letter, a correct alignment and spacing of the resulting print may readily be secured. Ordinarily the slide B will be placed with the 75 rear flange b' in the rear groove a' , but whenever it is desired to print a letter above the usual line the clip will be lifted and replaced with its flange b' in the forward groove a^2 , as indicated by dotted lines in Fig. 1 and more 80 clearly shown in Fig. 3. Obviously, an impression made by a type placed against the front flange b^2 of the clip when in this position will be raised above the line of the impressions made when the clip is engaged with 85 the rear groove a' by a distance equal to the distance between the grooves a' and a^2 . The type C' (indicated in dotted lines in Fig. 1) as employed for thus printing above the usual 90 line will ordinarily be smaller than the usual type C, and are more particularly designed for printing abbreviation and index characters.

As a means of enabling the slide B to be readily held against movement upon the 95 guide-strip during the making of each impression, each of the grooves a' and a^2 is made to incline slightly forward toward its bottom relatively to the plane of the flange b' of the slide. (See Figs. 2 and 3.) With this construction the flange b' will obviously bind in the groove when pressed down firmly upon the guide-strip, and thus prevent the slide from being easily moved. When, however, the front of the slide is raised slightly, the 100 planes of the flange and groove are made to coincide, thereby releasing the frictional engagement between them and enabling the 105

slide to be easily moved. Such relative inclination of the flange and grooves may obviously be provided either by placing the flange at right angles to the web b' and sawing the 5 grooves on a slight inclination from the perpendicular, as shown in Figs. 2 and 3, or by sawing the grooves in squarely and inclining the flange b' to the necessary degree, as shown in Fig. 5. The underlying principle is the 10 same in either case, however, and I consider both constructions within the scope of my invention.

The slide B itself, as herein shown, is conveniently made by bending down the edges of 15 a rectangular piece of sheet metal to form the flanges b' and b^2 and then riveting to the latter flange a second piece bent to an inverted-U shape and forming the arm b^3 . The handle b^4 may be secured to the web b by riveting 20 or otherwise. Obviously, however, the specific construction of the slide, aside from the features to which attention has been directed, is of minor importance and may be varied as desired.

25 The particular shape or configuration of the front edge a^3 of the guide-strip is not material, since the type are never brought into contact with it, but engage front flange b^2 of the slide instead, and since the flange b^2 itself 30 is supported and guided entirely independently of said front edge a^3 . As herein shown, however, said edge in cross-section is made in the form of an overhanging reverse curve, and is consequently adapted to serve as a 35 suitable guide for a ruling-pen, the necessity of turning the guide-strip over to enable such pen to be used without danger of the ink running or blotting along its edge being thereby obviated.

40 For the purpose of enabling the slide to be instantly set at any desired distance from the center or ends, the guide-strip A is provided with a graduated scale a^4 , extending from end to end thereof, such scale being in this instance marked upon the rear edge of the strip, 45 which is shown as beveled in the same manner as an ordinary ruler. The divisions a^5 of the scale a^4 , instead of being consecutively numbered from end to end, as in an ordinary 50 ruler, are numbered from the middle division toward each end, or, as herein shown, from "1" to "8," starting from the middle or zero point. The number of divisions, however, will obviously depend upon their length and the length 55 of the strip A, upon which the scale is placed. Each of the divisions a^5 is itself divided into subdivisions a^6 , in this instance eight in number, though either more or less may be employed, as desired.

60 Preferably the divisions a^5 will be of inch lengths and the subdivisions eighth inches. The subdivision lines marking the halves and quarters are also desirably differentiated in length from the others in the usual manner 65 to facilitate the reading of distances on the scale.

The object of thus numbering the scale di-

visions from the center toward each end of the strip is to enable the operator to readily determine where to begin a line of a given 70 number of words or other characters in order to have the end letters of the line equally distant from the side edges of the sheet upon which it is printed, or, in other words, in order that the printed line, when finished, will 75 stand in the middle of the sheet. To the same end the body or block c of each of the type C is made of a width equal to some multiple 80 of the subdivisions a^6 of the scale, the specific multiple varying according as the natural shape of the letter or sign requires a broader or narrower type, but being always an exact multiple. For example, the "E" type illustrated is made five-eighths of an inch, and most of the letters of the same font 85 would be made of this width. Obviously, however, the "M" and "W" would naturally require wider types, and the "I" and the punctuation-marks narrower ones. In a font of type of reduced size, such as the type C', 90 the width of the type would be proportionately reduced, but would still be made in multiples of the subdivision. The widths of the types being thus accurately known it is obvious that the length of the proposed line of 95 printing may be readily determined by summing up the total width of all the types required to print the letters forming the line and adding thereto the necessary allowance for the spaces between the words of the line 100 if it includes more than one word. When the length of the proposed line has been ascertained in the manner described, the guide-strip A is placed across the sheet S to be printed, and centered with relation thereto 105 by being moved endwise until the scale-readings are the same at each of the two side edges of the sheet. The slide B is then moved to the left of the center of the guide-strip a distance equal to one-half the ascertained 110 length of the proposed line, measured by the scale a^4 , and considering the right-hand side of the arm b^3 as the index-point. Said right side of the slide-arm b^3 will then obviously mark the beginning of the printed line—i. e., 115 the left-hand edge of the first letter thereof—and by moving the slide along after printing each letter a distance equal to the width of the type just used and allowing the predetermined spaces between words it is obvious 120 that the line will terminate just as far to the right of the center as its beginning was to the left thereof, or, in other words, the line will be placed exactly in the center of the sheet.

For example, let it be assumed that the 125 words "Lowest prices" are to form one of the lines to be printed with a font of upper-case or capital-letter types similar to the type C illustrated. Assuming the ten types besides the "W" and "I" types as five-eighths wide 130 each, the "W" type as seven-eighths, and the "I" type as two-eighths, and allowing three-eighths for the space between the words, the total length of the line will obviously be sixty-

two eighths or sixty-two of the subdivisions a^6 . The slide B is therefore moved to the left of the center of the guide-strip until the right-hand side of its arm b^3 registers three and 5 seven-eighths, (one-half of sixty-two eighths,) the guide-strip being itself centered on the sheet S by so placing it that the side edges s of the sheet register alike on the scale, (four and three-quarters, for example, in Fig. 1 L.) 10 The printing is then proceeded with in an obvious manner by thrusting each type in its order into the corner formed by the right-hand side of the arm b^3 and the front flange b^2 , and then making the impression therewith. 15 As each letter is printed the slide B is moved to the right a distance equal to the width of the preceding type. Such distance may be practically determined without reference to the scale by simply moving said slide until the right-hand side of its arm b^3 stands above 20 the right-hand edge of the letter just previously printed. The slide will thus be moved five-eighths after each of the letters except the "W" and "I" has been printed, seven- 25 eighths after the "W," and two-eighths after the "I." An extra movement of three-eighths will also be given the slide after the "T" to allow for the space between the words. This distance may be measured by the scale, but 30 as a convenient construction in this connection the arm b^3 is in this instance made of approximately the width of the desired space between words, so that moving the scale until the left-hand side of its arm b^3 stands above 35 the right-hand edge of the last letter of a word determines the position of the first letter of the next word. The correct space between letters is secured by making the letter or printing face c' of the type slightly narrower than the width of its block or body c , as in ordinary cast printing-type, so that the edge of the impression will necessarily be a slight distance in from the edge of the type-block. 40 As a result of the procedure described, it will be obvious that the final letter "S" of the line will necessarily be printed as far to the right of the center of the sheet as the first letter "L" is to the left thereof, so that the line 45 as a whole is placed centrally upon the sheet without its having been necessary for the operator to pay any attention to its prospective termination after locating its commencement. 50 The width of each of the several types of each font may for convenience be marked upon the type themselves, as shown at c^3 in Fig. 1, and a complete list of the widths is desirably placed upon the inside of the cover or on some other suitable part of the box in 55 which they are packed. Obviously, however, the operator would readily remember the widths after using the type a short time, and could, moreover, readily determine the width of any type concerning which he has any doubt 60 by measuring it upon the scale. 65 The construction of straight-edge or ruler

shown, in which the divisions of the scale are numbered from the middle toward each end, may be found useful in other connections than that hereinbefore set forth, and is accordingly 70 claimed separately therefrom as well as in connection therewith.

I claim as my invention—

1. A type guide for hand printing comprising a guide strip provided in its top surface 75 with a longitudinal guide groove, and a slide provided with a flange adapted to enter said groove, the lower edge of one side of said flange being normally engaged with the adjacent side of the groove and the upper edge of the 80 opposite side of the flange with the opposite side of the groove, whereby the slide is held against movement by friction when resting in its normal position, and type engaging surfaces on said flange arranged parallel with and 85 at an angle to said guide strip, substantially as described.

2. A type guide for hand - printing with types of different sizes, comprising a guide strip provided on its upper surface with two 90 longitudinal grooves, having parallel side walls and arranged parallel with each other, and a slide provided at its front and rear edges with depending flanges located at a distance apart as great or greater than the distance between the side edge of the guide strip and the groove which is located at the greatest distance therefrom; the flange at the rear edge of the slide being adapted to engage both sides of the grooves of the guide strip and the flange 95 at the outer edge of the slide having a type-engaging arm which projects therefrom at an angle with the said flange, substantially as described.

3. A type guide comprising a guide strip 105 provided in its upper surface with a longitudinal groove and a slide provided with a groove-engaging flange and with type-engaging surfaces parallel with and at an angle to the said groove, the plane of the said groove being 110 slightly inclined to the plane of the flange which enters the same, whereby the slide will be held from movement when its outer edge is depressed, substantially as described.

4. A type guide comprising a guide strip 115 provided in its upper surface with a longitudinal groove and a slide comprising a metal plate having depending flanges on its opposite edges, one of which flanges is adapted to engage the grooves in the guide strip and provided also with a type-engaging arm which projects from the forward flange of said slide, the said groove being inclined relatively to the flange which engages the same, substantially as hereinbefore set forth. 120 125

In testimony that I claim the foregoing as my invention I affix my signature in presence of two witnesses.

LOUIS K. SCOTFORD.
